TARGET-PRACTICE APPARATUS.

1,014,620.

Specification of Letters Patent.

Patented Jan. 9, 1912.

Application filed August 16, 1905. Serial No. 274,424.

To all whom it may concern:

Be it known that I, HENRY H. CUMMINGS, a citizen of the United States, residing at Newton, in the county of Middlesex, State 5 of Massachusetts, have invented an Improvement in Target-Practice Apparatus, of which the following description, in connection with the accompanying drawings, is a specification, like letters on the drawings 10 representing like parts.

My invention relates to target practice apparatus and more particularly to the class 15 of target practice apparatus employing means for recording the aim without the necessary issuance of any projectile from the aiming device, such by way of example as is described in United States Patent No. 739,778, granted to me September 22, 1903.

In the patent referred to there is specifically disclosed a target practice apparatus employing an aiming device, therein a gun, adapted to be aimed at a main target but so connected with following means, including a recording needle, that the latter is 20 caused to follow the aiming movements of the aiming device relatively to a secondary or miniature target. At the time of firing, whether actual or simulated, the aim is permanently recorded upon the secondary target 25 by movement of the latter toward and against the point of the recording needle and without the necessary issuance of any projectile from the gun, the relations between the aiming device, the main target, 30 the needle and the secondary target being such that the line of sight of the aiming device relatively to the main target, is at all times faithfully reproduced by the needle with reference to the secondary target.

My present invention provides a simple but effective construction of target practice apparatus which is particularly desirable where a considerable freedom of movement is required for the aiming device, such, for 35 example, as ordinarily accompanies the use of a revolver which when used either in practice or actual use, is often swept

through a considerable range of movement before deliberate and final sight is taken upon the distant object.

My invention will be best understood both as to the features suggested by the foregoing paragraph and other features of novelty which the same involves by reference to the following description, when taken in connection with the accompanying illustration of one specific embodiment thereof submitted for illustrative purposes, while its scope will be more particularly pointed out in the appended claims.

Of the drawings, Figure 1 is a side elevation of a target practice apparatus embodying one form of my invention and intended for use in connection with a revolver; Fig. 2 is a plan view of one end of the apparatus 65 illustrated in Fig. 1, showing on a larger scale the revolver and recording mechanism; Fig. 3 is a similar view in side elevation; Fig. 4 is a section on the line 4—4 in Fig. 3, looking toward the sub-target; Fig. 5 is a 70 section on the line 5—5, Fig. 3, looking toward the revolver; Fig. 6 is a side elevation of that end of the apparatus carrying the target at which aim is taken; Fig. 7 is a front elevation thereof; and Fig. 8 is a 75 section on the line 8—8 in Fig. 3.

In the illustrated embodiment of my invention the aiming device *a*, which may be of any desired type or construction, but which herein is a revolver of the Colt army 80 type, is so associated with a relatively distant target *b*, at the opposite end of the apparatus, that a free aiming movement of the revolver, relatively to the target, is permitted the marksman. As in the case of the 85 target practice apparatus disclosed in my prior patent, deviations of the line of sight of the revolver from the bull's-eye are, by the connections hereinafter described, duplicated by the corresponding deviations of a 90 recording needle *c* which moves with reference to a sub- or secondary target carried in the target holder *d*, so that when the sub-target, which, for this purpose, is movable

is forced against the point of the needle, the resulting impression made thereby correctly records upon the face of the sub-target the aim taken at that instant by the revolver 5 with reference to the main target *b*. The latter presents an aim-fixing spot at which aim may be taken, such spot herein comprising the bull's-eye (see Fig. 7) on the face of the said main target *b*.

10 In the present apparatus the revolver, sub-target and main target are carried upon suitable supporting means, which may assume various forms, but is preferably constructed of a simple piece of steel tubing *e*. 15 This affords the desired lightness and low inertia, while giving the maximum rigidity and stiffness.

At one end of the steel tubing is carried the main target *b*. Referring to Figs. 6 and 20 7, this target, in the present instance, is removably and slidably carried in a target holder *b*², the latter, in its turn, being adjustably slidable upon a standard *b*³ carried by the bracket *b*⁴, here shown as provided 25 with a split sleeve embracing and clamped to the steel tubing *e*. The target holder may therefore be adjusted vertically upon the standard, and there clamped or otherwise fixed in any desired position, as by the set 30 screws *b*⁵, change in such adjustment, however, being infrequently required.

The apparatus may be supported in any suitable way, but I have herein shown the entire support *e*, with its attached revolver, 35 sub-target and main target mounted for free movement about a point which here substantially though not exactly co-incides with the bull's-eye of the target. For this purpose the grooved supporting pin *b*⁶, 40 rests in the collars *b*⁷ (Fig. 1), the latter being fastened to the depending suspension members *b*⁸, which are herein attached for swinging movement to the ceiling or other suitably elevated overhead support, the connection being such that the apparatus is 45 supported at the target end thereof and without offering any substantial resistance to lateral, vertical, gyratory or other movements imparted to the aiming device at the 50 opposite end of the tube.

In order to relieve the marksman of the weight of the attached moving parts and to leave him sensible of the weight of the revolver only, counterbalancing means are connected with the apparatus, this, in the illustrated example, consisting of the weight *f*, connected to the flexible cord *f*', which passes over the stationary pulley *f*³ and is connected to the U-shaped frame *f*⁴, which 55 has one branch attached to the sub-target bracket *d*', and the other to the cord *f*'. The weight *f* is of a size sufficient to counterbalance the weight of the apparatus less the weight of the revolver, so that when the 60 latter is moved up or down about the point 65

of suspension, the marksman is relieved of all but the weight of the revolver itself.

The butt of the revolver is secured to an arm *a*' (see Figs. 2 and 3), the latter being pivoted at *a*² to the vertically swiveled pin *a*³. The pin *a*³ turns in a socket in the bracket *a*⁴, the latter being clamped to the end of the rod *e*. This construction permits the revolver to be swung with the swiveled pin in a horizontal plane and about the 75 pivot *a*² in a vertical plane. The revolver therefore has a universal connection to the supporting rod, permitting what may be termed, a free aiming movement of the fire-arm, resulting in deviations in the line of 80 revolver sight with reference to the main target, such a movement, for example, as a revolver undergoes about the wrist of the marksman as a fulcrum, or a rifle undergoes about the marksman's shoulder as a 85 fulcrum. It will be seen, however, that this aiming movement is not in the least constrained and there is no aiming point-of-rest, for the fulcrum or fulcra about which it takes place, is not fixed, but like the wrist 90 or hand of the marksman holding a revolver in actual practice, may travel horizontally or vertically with substantially no opposition.

During the aiming movement of the revolver or such movement as produces deviations in the line of revolver sight from the bull's-eye of the target, the recording needle *c* is caused to undergo similar movement about a pivot post having a spherical head *c*' (Figs. 2 and 3), adjustably threaded by means of the thumb nut *c*², into the bracket *c*², the latter fixed upon the tube *e*. The needle is secured to the needle head *c*⁴, and the latter is provided with a vertical bore of substantially the same diameter as the spherical support *c*', the lower end of the bore being flared to permit a suitable range of needle movement upon the support, and the upper end being closed by the pin *c*⁵, which rests upon the spherical head and by which the needle is sustained. This provides a delicate pivot post suspension for the needle similar to that of a compass needle, permitting free gyrations of the 110 needle about the post and at the same time the ready detachment of the needle from its support by merely lifting the head therefrom.

To the head of the needle is clamped the 120 yoke *g*, having the two rearwardly extending arms *g*' and *g*², carrying the counterbalancing weights *g*³ and *g*⁴. The weights are of such a size and so located as to press the needle upward about its support and also 125 to give an appreciable mass to the needle, providing sufficient inertia therefor for a purpose to be referred to. The weights are preferably adjustable along the arms *g*' and *g*², and provided with clamping screws as 130

indicated, to effectually retain them in their positions, change in which will seldom be required. The location of the weights below the center of needle suspension adds considerably to its stability and also prevents the needle from turning on its axis, which, if it be bent or out of true, may result in an erroneous record.

The revolver arm a' is connected to the needle c by the overhanging connecting member h , which is yieldably seated upon the cylindrical end a^5 of the arm. The connecting member has two feet, h' and h^2 , cut as shown in Fig. 8, to seat upon the curved surface of the arm and is held seated thereagainst by the flat leaf spring h^3 , secured at one end to the connecting member h and pressed down at its opposite end by the nut h^4 , adjustable on the threaded stud h^5 , which latter is secured to the cylindrical end of the revolver arm but passes loosely through the connecting member h . By this arrangement the arm is connected with the needle to compel the latter to follow the movements of the revolver; but under any unusual resistance the needle will yield relatively to the revolver. Thus, the end of the connection which engages the needle may be raised against the elasticity of the spring upon the foot h' as a fulcrum, or may be shifted horizontally to one side or the other by the unseating of the feet h' and h^2 , and the swinging of the connecting member about the stud h^5 . The opposite end of the connecting member is provided with the down-turned guiding finger h^6 (Fig. 5), having the flared opening h^7 , the center or apex of which is adapted to engage the needle c and direct the movement thereof. As the revolver is swung upwardly and the finger h^6 raised, the needle, being gently pressed toward the apex of the opening by the weights g^3 and g^4 , is caused to follow the movement thereof. If the revolver is depressed, the finger also depresses the needle, raising the counterbalancing weights g^3 and g^4 . Movement of the revolver in a horizontal plane directs a corresponding movement of the needle about its support.

To effect the record of the aim by forward movement of the sub-target against the needle point when the revolver trigger is pulled, there is provided suitable motive mechanism, herein electromagnetic. The sub-target j (Figs. 3 and 4) is removably held in a vertically curved target holder d , the latter having the rearwardly projecting tubular support d^2 , slidably mounted in the bracket d' and adapted to be moved forward by movement of the lever d^3 . The latter is pivoted at d^4 and has its upper end working in a transverse notch in the under side of the projecting end of the tubular support. The target and its holder are normally retracted or withdrawn out of contact with

the needle point by the pressure of the pin d^5 against the edge of the lever d^3 , the pin being seated in the bracket and pressed outward by a spiral spring. The sub target j presents to the needle a suitable bull's-eye 70 as shown in Fig. 4 adapted to receive the mark of the marking needle, the center of the bull's-eye being covered by the needle point when the revolver is correctly aimed at the center of the aim fixing spot.

Hooked about the lower end of the lever d^6 , which enters within the tube e , is the lever actuating member d^6 , which herein consists of a small wire or rod. The latter passes to the target end of the tube and has 80 a projecting threaded end (Fig. 6) passing through the armature lever k , to which it is adjustably secured by means of the threaded nut d^7 . The armature lever k is controlled by the electro-magnet k' . When the latter 85 is energized, the armature is attracted and the connecting member d^6 retracted to throw the target holder forward and cause the face of the target to be punctured by the neede.

The magnet is energized and the record takes place when the trigger is pressed in simulation of the act of firing by means of the electric circuit indicated in the drawings. This includes the electro-magnet k' , 95 the battery l , and circuit-closing mechanism associated with the revolver itself. The conductor m , (Fig. 1) connects one pole of the battery l with the electro-magnet k' ; the other pole of the battery being connected 100 by the conductor m' with the binding post n , the latter being carried by the bracket n' near the revolver end of the tube. The remaining terminal of the magnet is connected by the conductor m^2 with a second 105 binding post n^2 , upon the said bracket n' , the two conductors m' and m^2 passing from the magnet to the bracket n through the interior of the tube.

To the opposite ends of the binding posts n and n^2 are connected respectively the free ends of the revolver lead wires o and o' , the opposite ends of the latter passing into the butt of the revolver and connected to the contact pieces o^2 and o^3 . The revolver butt is shown in Fig. 3 with one face removed to illustrate the construction of the circuit-closing mechanism. The contacts o^2 and o^3 remain normally in separation, but are brought together when the trigger is pressed 110 by the sliding presser block o^4 of insulating material pivoted to the lever o^5 , the latter having a depending extension o^6 directly back of the revolver trigger a^6 . The ends 115 of the contact pieces enter the opening o^7 in the lower end of the sliding block o^4 , so that when the trigger is pulled and the contact block is raised in response to the movement of the lever o^5 , the walls of the contracted opening o^7 , draw the diverging 120

125 130

ends of the contact pieces together and complete the electric circuit. This form of circuit-closing mechanism is very satisfactory, since it can be placed in the waste space in 5 the revolver butt without any substantial alteration in the ordinary army revolver. It is so sensitive that the trigger cannot be pulled to throw the hammer without insuring the completion of the circuit, while, on 10 the other hand nothing short of a pull upon the trigger sufficient to throw the hammer will cause the energization of the magnet.

When the apparatus is out of use, the revolver may be held in a fixed position by 15 means of the hinged rest p , which, when thrown into the dotted line position shown in Fig. 3, receives the end a^6 of the revolver arm in an appropriate groove, and holds the revolver centrally against lateral or 20 downward movement. With the apparatus adjusted, the revolver when thus held by the hinged rest, should ordinarily sight at the bull's-eye, and the needle should be directly opposite the bull's-eye of the sub-target.

25 With the apparatus in proper adjustment and the hinged support p thrown down, as shown in Fig. 3, to release the revolver and the following parts, the marksman may grasp the revolver and aim at the main target, the fire-arm being perfectly free to undergo any of the usual evolutions which its holder may find desirable or needful. The entire apparatus, on account of its floating suspension, is free to yield to those arm 30 movements involving lateral or vertical sweeps, or a twisting or swinging of the fire-arm, while that characteristic downward sweep of the revolver for positioning the same prior to firing, in which it is the habit 35 of many marksmen to indulge, is freely permitted by reason of the hinged connection of the revolver to its support, coupled with the floating suspension. If the revolver is pointed upward prior to a downward 40 sweep, the finger h^6 will be lifted away from the needle, movement of which however is restricted to the face of the target by the limiting frame r . When the revolver is 45 swept down, the flaring mouth of the finger will embrace the needle and re-assume the control thereof as soon as the line of sight of the revolver crosses the field of the main target. The revolver is therefore perfectly free to be swept out of the field of the main 50 target, but is adapted to re-assume control of the recording needle as soon as it re-enters the field thereof.

If the line of revolver sight is depressed 55 so far as to bring the needle against the lower boundary of the limiting frame, its connection to the revolver will yield by the raising of the foot h^2 about the foot h' as a fulcrum. If swung too far laterally, the connecting member h will merely unseat 60 itself from the revolver arm. Obviously,

means might be provided for causing the reseating of the connecting member upon the arm when, after it has been displaced by excessive lateral movement of the revolver, the line of sight re-enters the field of 70 the main target, but I have found that the positioning movements practiced by marksmen are principally or wholly vertical movements, and the unseating of the connecting member from the revolver arm is provided 75 principally as a protection against injury to the needle through accidental lateral displacement of the fire-arm, rather than a feature to be called into frequent use.

During gyrations of the revolver, all such 80 movements thereof as result in a deviation of the line of revolver sight from the bull's-eye of the main target, are faithfully reproduced by corresponding deviations of the needle from the bull's-eye of the sub-target. 85 It will be observed that when the position of the aiming device is changed without deflection relatively to the main target,—in other words, when it executes a positioning movement as distinct from an aiming movement 90 the recording devices, including the needle and sub-target move with the aiming device without, however, executing any relative movement save when the aiming device undergoes aiming movement. 95

Aim having been taken at the main target, and the trigger pulled, the circuit is thereby closed, the magnet energized, and the target thrown forward against the needle point to receive the record of the aim, all 100 of which will be readily understood from the preceding description.

In case the marksman does not immediately release the trigger, the target will remain in contact with the needle point, but 105 no injury will result from simultaneous movement of the revolver, either to the target or the needle, on account of yielding connection between the latter and the needle which, it will be observed, permits yielding 110 in all directions, both laterally and vertically. After one record has been made, other records may be made upon the same sub-target, or the latter may be withdrawn from 115 its holder and a fresh target substituted for a continuation of the practice.

The magnet k obviously might be located at or adjacent the sub-target, but since the magnet is one of the heaviest elements of the described apparatus, I prefer to position it near the point of suspension, so as to decrease, so far as possible, the mass of the apparatus near the revolver end. The weight of the parts of the apparatus near the revolver end need be but comparatively 120 small. I have found in practice that with a suspension of five or six feet in length and a tube of from six to eight feet long, with a proper counterbalancing of the apparatus, the marksman feels substantially 125 130

no resistance to the movement of the fire-arm beyond the weight of the revolver itself. The dimensions, as well as the entire construction of the apparatus, may be quite different from that disclosed; but when constructed as described, and for revolver practice, I prefer to make the support of approximately the length suggested, obtaining the effect of any desired greater length of range by an appropriate reduction of the standard targets for the increased range. For example: in the illustrated embodiment of my invention, the main target b , is a standard thirty yards revolver target appropriately reduced, however, to suit the diminished distance at which it is used. The sub-target, as will be understood from my prior patent referred to, is so proportioned to the main target as to correctly record thereupon the aim taken at the former.

In order to assist in the correction of defective eye-sight, that is to say, to compensate for the errors of those marksmen who repeatedly sight too high or low, or to the right or left of the bull's-eye, which subject is fully set forth in my aforesaid prior patent, there is provided means for adjusting the relation between the line of sight, the marker, the bull's-eye and the aim-fixing spot to offset the marker from a vertical line through the bull's-eye when the line of sight is directed on the aim-fixing spot. Herein the relation between these four elements is adjusted by adjusting the needle or marker laterally from its normal or true position. To effect this, the finger h^6 (Figs. 2 and 3) is pivoted to the arm h by means of the stud s and carries at its opposite end a graduated head s' , by which it may be clamped through the clamping screw s^2 , so as to bring any one of the several graduations opposite the stationary zero mark s^3 . The graduations, are expressive in different degrees of the tendency to shoot to the right or left of the bull's-eye, this showing the marksman the amount necessary to offset the needle to eliminate this tendency. As set forth in the aforesaid prior patent, this may be utilized, first to acquaint the marksman with his defect, and finally to correct the defect by causing him to make an unconscious allowance therefor. With short ranges, such as are required in revolver practice, correction of eye-sight for vertical displacement is usually unnecessary, but if such correction is desired, it may be accomplished by adjusting the main target vertically above or below its true position, there being provided for this purpose graduations s^4 , upon the target standard, by which the amount of vertical displacement may be judged.

The needle suspension described I have found in practice particularly sensitive and efficient. The weights g^4 cause the needle to

remain under the control of the revolver finger h^6 , for any ordinary aiming movements. The needle is pressed against the finger so delicately that its pressure cannot be perceived or felt by the holder of the fire-arm. The weights also provide a certain inertia for the needle, which is desirable if practice with blank ammunition is required.

In order to accustom the marksmen to the shock of the explosion, blank cartridges may be fired with the revolver if the kick or recoil of the fire-arm, which, on the actual range does not affect the trajectory of the bullet, can be eliminated from the record. The recoil usually occurs before the completion of the record and is apt to introduce an error in the aim if the needle is too quickly responsive to the recoil movement of the revolver. In the present instance, a recoil which will throw up the muzzle of the revolver, merely lifts the finger from the needle, and the latter, by reason of the inertia of the weights, does not immediately move. The interval occupied in overcoming the inertia of the needle, though slight, is sufficient for completion of the record and such record therefore shows the aim at the moment of firing and before recoil instead of after recoil, as would often or always be the case if there were an unyielding connection between the revolver and the needle.

Re-adjustment of the apparatus to a normal position, that is to say, where the revolver, when held by the hinged rest p , points to the center of the bull's-eye of the distant sub-target, and the needle simultaneously points to the bull's-eye of the sub-target, will only be necessary when there has been injury to or displacement of some of the parts. Such adjustment if needed, however, can be easily made. The line of revolver sight can be adjusted laterally with relation to the target by unloosening the clamping screw which secures the bracket carrying the hinged rest to the tubular support and twisting the same slightly upon the support before reclamping it, or the same may be done with the target carrying bracket b^4 . Vertical adjustment of the line of sight relative to the target may be had by sliding the target frame up or down in the tightly fitting holder b^2 . Vertical adjustment of the needle relatively to the sub-target is had by turning the thumb nut c^3 , and lateral adjustment by unclamping the bracket c^2 and turning it upon the tubular support.

It will be seen that the common carrier comprising the tube e maintains the target b and the recording target j in definite relation one to the other and that in the normal adjustment of the apparatus such relation is determined or selected with reference to the relation of the marker or needle and the aiming device. Obviously when in normal adjustment with the revolver pointing

at the center of the aim-fixing spot when the needle simultaneously points at the center of the bull's-eye of the sub-target, such relation requires that the aim-fixing spot shall stand at a distance above the bull's-eye approximately equal to the line of sight of the revolver above the line of action or axis of the marker when pointing at the bull's-eye.

10 In order to enforce the practice of quick sighting and firing, if desired, use may be made of a shutter or screen *w*, shown suspended in Fig. 1, in front of the main target. This screen can be swung aside to expose the main target to the vision of the marksman for a definite brief period only, at the end of which it may be allowed to swing back into place in front of the target to obscure the same. The marksman is supposed to sight and fire during the interval the target is exposed. Obviously, automatic shutter mechanism for exposing the target for a given period may be employed, but the device indicated is simple and effective 25 for ordinary purposes.

Obviously it is not necessary, although desirable, to support the apparatus at or near the main target, and such supporting point might be located at some other position 30 in the apparatus than that shown. While the overhead suspension members contribute a simple but effective support to the apparatus, it will also be obvious that the effect of a floating suspension or a freely 35 movable support may be obtained in other ways than that disclosed, such, for example, as by mounting the target end of the apparatus upon frictionless rollers and permitting it to roll over a suitable platform 40 or table, or in other ways unnecessary to mention. It must also be understood that while my invention comprehends a support so movable as to offer little or no restriction 45 to the efforts of the marksman in positioning the fire-arm, yet in many features my invention is not limited thereto, but is susceptible of useful application where such a freely movable support is not provided or 50 where apparatus of quite different construction is employed.

While I have shown and described one embodiment of my invention for illustrative purposes, it is to be understood that the same is not limited to the form, construction 55 and arrangement of parts here shown, but that extensive modifications thereof may be made without departing from the spirit of my invention.

Claims:

60 1. A target practice apparatus having an aiming device, means for indicating the aim thereof without the necessary issuance of a projectile, and a freely movable support upon which said aiming device has aiming 65 movement.

2. A target practice apparatus having an aiming device for aiming at a target or like object, a freely movable support upon which said aiming device is fulcrumed, and following means to follow the aim of said device with relation to a reference object. 70

3. A target practice apparatus having an aiming device for aiming at a target or like object, following means to follow the aim thereof and a freely movable support for said aiming device and following means. 75

4. In an apparatus of the class described, an aiming device for aiming at a target or like object, following means to follow the aim thereof with relation to a reference object, and a common freely movable support for said aiming device, following means and reference object. 80

5. In a target practice apparatus having an aiming device for aiming at a target or like object, following means to follow the aim thereof with relation to a reference object, and supporting means for said aiming device, following means and reference object movable about a point substantially 90 coincident with said target.

6. In a target practice apparatus, a main target, a secondary target, an aiming device, and a movable support for said main target and upon which said aiming device has aiming movement. 95

7. A target practice apparatus having an aiming device and means for indicating the aim thereof without the necessary issuance of a projectile, said aiming device being 100 movably mounted upon a freely swinging support.

8. A target practice apparatus having an aiming device, a main target, and a secondary target, and a movable tubular support common to said main target, secondary target and aiming device. 105

9. In an apparatus of the class described, an aiming device, a support upon which said aiming device is fulcrumed, a main target 110 also upon said support, and means permitting the movement of the latter during any movement of said aiming device.

10. A target practice apparatus having a floating support, and aim recording means thereon comprising an aiming device, a main target and a secondary target. 115

11. A target practice apparatus having an aiming device for aiming at a target or like object, following means to follow the aim thereof with relation to a reference object, a support upon which said aiming device is fulcrumed for aiming movement thereof, said support being movable to permit of positioning of said aiming device when in the hands 120 of the marksman and said following means being mounted upon said support.

12. A target practice apparatus having an aiming device, means for recording the aim thereof without the necessary issuance of a 130

- projectile, and a flexible suspension for said aiming device and said recording means.
13. A target practice apparatus having an aiming device, a main target, a secondary target, a movable support for said aiming device and secondary target, and an electromagnet for recording the aim on said secondary target, said magnet being located near the center of movement of said support.
- 10 14. A target practice apparatus having an aiming device, means for indicating the aim thereof without the necessary issuance of a projectile, and electric actuating means therefor, comprising a contact device, and an actuating lever adapted to be moved on the pulling of the trigger and a freely movable support for said aiming device and said actuating means.
- 15 15. A target practice apparatus having an aiming device, a support, connections between said support and said aiming device permitting aiming movement of the latter, means for indicating the aim thereof without the necessary issuance of a projectile, and a pivoted rest to retain said aiming device in its normal position when out of use.
- 20 16. A target practice apparatus having an aiming device for aiming at a target or like object, and following means to follow the aim thereof with relation to a reference object, said following means including a pivotally supported indicating pointer having a counterbalancing weight below the center of pivotal support.
- 25 17. A target practice apparatus having an aiming device for aiming at a target or like object, a vertically adjustable pivot pin and a gravity sustained pointer on said pivot pin and connected to follow the aim of the aiming device.
- 30 18. A target practice apparatus having an aiming device for aiming at a target or like object, and following means to follow the aim thereof with relation to a reference object, said means including a gyratable pointer, a directing member, and a counterbalancing weight by which said pointer is pressed toward said directing member.
- 35 19. A target practice apparatus having an aiming device for aiming at a target or like object, and following means to follow the aim thereof with relation to a reference object, said means including a fulcrumed pointer and a guiding member engaging said pointer between the point thereof and its fulcrum and adapted to be withdrawn therefrom on excessive aiming movement of the aiming device.
- 40 20. A target practice apparatus having an aiming device for aiming at a target or like object, and following means to follow the aim thereof with relation to a reference object, said means including an indicating pointer and connecting means between said aiming device and said pointer yieldable to

permit excessive movement of said aiming device in any direction without necessary movement of said pointer.

21. A target practice apparatus having an aiming device for aiming at a target or like object, and following means to follow the aim thereof with relation to a reference object, said means including an indicating member and connections between said indicating member and said aiming device and means for adjustably offsetting said member laterally from the aiming device.

70 22. A target practice apparatus having an aiming device for aiming at a target or like object, a main target to be aimed at following means to follow the aim thereof with relation to a reference object, and means for exposing and thereafter obscuring the main target.

75 23. A target practice apparatus provided with an aiming device, a movable support therefor, said device having an aiming movement about said support for aiming at a target or like object and having also, while in the hands of the marksman, a positioning movement with and upon said support, a follower therefor to follow and indicate the aim thereof by movement relative to a reference object, said follower performing its relative indicating movement only upon the aiming movement of the said aiming device.

80 24. A target practice apparatus having an aiming device, a support on which said aiming device is fulcrumed, an arm projecting beneath said aiming device and in the same direction therewith and secured thereto for movement with the same about its fulcrumed support, an indicating pointer also fulcrumed upon said support and means for connecting said arm and pointer to direct the movement of the latter, said connection permitting withdrawal of said directing means from said pointer on extreme movement of said aiming device.

85 25. A target practice apparatus having an aiming device for aiming at a target or like object, a main target and a reference object such as a sub-target, a movable support upon which said aiming device is fulcrumed and following means to follow the aim of said device with relation to said reference object.

90 26. A target practice apparatus having an aiming device for aiming at a target or like object, a main target and a reference object, a movable support upon which said aiming device, main target and reference object are mounted, and following means to follow the aim of said aiming device with relation to said reference object.

95 27. A target practice apparatus having an aiming device, a target or other like object at which aim may be taken, a reference object, following means to follow the aim of said aiming device with relation to said

- reference object, and supporting means for said aiming device movable about a point substantially coincident with the said target.
28. A target practice apparatus having a main target, a secondary target, an aiming device and following means and a common movable support for said main target, secondary target, aiming device and following means.
29. A target practice apparatus having a main target, a secondary target, an aiming device and following means and a freely movable support for said main target, secondary target, aiming device and following means.
30. A target practice apparatus having an aiming device for aiming at a target or like object, a main target and a reference object, following means to follow the aim of said aiming device with relation to said reference object and means connecting the main target and aiming device to maintain the desired relation between the same.
31. A target practice apparatus having an aiming device for aiming at a target, a main target, a reference object, following means to follow the aim of said aiming device with relation to said reference object, and a movable support connecting the main target and aiming device to maintain the desired relation between them.
32. A target practice apparatus having an aiming device, means for recording the aim thereof without the necessary issuance of a projectile, a main target and a flexible suspension for said aiming device and main target.
33. A target practice apparatus having an aiming device, means for recording the aim thereof without the necessary issuance of a projectile, a main and a sub-target and a flexible suspension for said aiming device, main and sub-targets.
34. A target practice apparatus having an aiming device, means for recording the aim thereof without the necessary issuance of a projectile, a main target, following means to follow the aim of the aiming device with relation to a reference object, and a flexible suspension for said aiming device, main target, reference object and following means.
35. A target practice apparatus having an aiming device for aiming at a target or like object, following means for following the aim thereof with relation to a secondary target, and electro-magnetic means for effecting the record of the aim upon said secondary target and a support for said electro-magnetic means connected to move with said aiming device.
36. A target practice apparatus having an aiming device for aiming at a target or like object, following means to follow and indicate the aim thereof with relation to a reference object, said following means including an indicating pointer and a single pivot post support on which the same has universal movement.
37. In a target practice apparatus, the combination of a member having a free swinging movement about one end and an aiming device connected adjacent the other end of said member having a universal movement relative thereto and adapted to be held and operated by one hand.
38. In a target practice apparatus, the combination of a member having a free swinging movement about one end and an aiming device connected adjacent the other end and having a universal movement relative thereto, and counterbalancing means for said member to permit free positioning or aiming movement of said aiming device in simulation of usual firing conditions thereof.
39. In a target practice apparatus, the combination of a member having a free swinging movement about one end and an aiming device connected adjacent the other end and having a universal movement thereon, and recording means comprising a follower connected with said aiming device to follow the aim thereof and a target medium on which relative position of said follower is recorded at time of simulated or actual firing.
40. In a target practice apparatus, a gyroscopic follower provided with a pivotal support and a pair of rearwardly extending arms g^2 having weights g^4 adjustably secured thereon.
41. A target practice apparatus having an indicating needle, a support, an aiming device mounted on said support, an indicating needle, a guiding member connected to said aiming device to direct the movement of said needle but movable relatively to the latter, and means for weighting said needle for throwing it toward said guiding member.
42. In a target practice apparatus, the combination with an aiming device, of a fulcrumed indicating needle therefor, the latter mounted for gyroscopic movement, a guiding member for said needle, and means tending to press said needle toward the said guiding member while at the same time preventing it from turning about its axis.
43. The combination with an aiming device having a trigger, electrically actuated contact means for indicating the aim thereof, electrical contact means controlling said indicating means and carried by said aiming device, the same comprising a pair of resilient contact members, a block actuated by the trigger having a recess provided with a narrow opening and receiving the ends of said contact members and adapted upon move-

ment of said trigger to bring said ends together.

44. In a target practice apparatus, an aiming device, having a trigger a^6 , a lever o^5 , adapted to be clutched thereby and provided with a block o^4 having a recess o^7 , and electrical contact devices o^2, o^3 entering said recess and engaged by the walls thereof upon actuation of said lever to bring the same into electrical contact.

45. In a target practice apparatus the combination with a main target b , aiming device a , connection e between the aiming device and main target, needle c and sub-target d .

46. In a target practice apparatus the combination with an aiming device adapted to be aimed at a target, a follower adapted to follow the aiming movement thereof relatively to a reference object, and a flexible cord-like connection between said aiming device and a fixed extraneous object permitting free positioning movement of the aiming device without deflection of the follower relatively to the reference object.

47. In a target practice apparatus the combination with an aiming device adapted to be aimed at a target, a follower adapted to follow the aiming movement thereof, and a support movable with the aiming device upon which support said follower is movably mounted.

48. The combination with an aiming device of a universally mounted follower adapted to follow the deflections of the aiming device to an exaggerated degree, and a support for said follower movable with the aiming device during aiming movement.

49. A target practice apparatus having an aiming device, a main target, means for indicating the aim thereof without the necessary issuance of a projectile and a freely movable connection leading from the aiming device substantially to the main target.

50. The combination with an aiming device of a follower adapted to follow the aim thereof, a sub-target upon which the follower acts to record the aim, and a support for the sub-target movable with the aiming device during aiming movement.

51. The combination with an aiming device of a follower adapted to follow the aim thereof, a sub-target, and a support for the follower and sub-target movable with the aiming device during aiming movement.

52. A target practice apparatus having an aiming device, a main target, means for indicating the aim thereof without the necessary issuance of a projectile, and a freely movable connection between the main target and the aiming device.

53. A target practice apparatus having an aiming device for aiming at a target or like object, following means to follow the aim

thereof with relation to a reference object, 65 and movable connecting means extending from the aiming device to substantially the main target to maintain the desired relation between the same.

54. The combination of an aiming device 70 of a main target, a follower, recording means, and a flexible connection permitting free movement together of the aiming device and the recording means.

55. A target practice apparatus comprising 75 a main target, an aiming device having both a positioning and an aiming movement and indicating devices movable relatively to each other on aiming movement of the aiming device and movable with the aiming device without movement relatively to each other on positioning movement of the aiming device.

56. A target practice apparatus comprising 80 a main target, an aiming device having both a positioning and an aiming movement and recording devices movable relatively to each other on aiming movement of the aiming device and movable with the aiming device without movement relatively to each other on positioning movement of the aiming device.

57. In a target practice apparatus the combination with an aiming device adapted to be held and operated by one hand of the 95 marksman, of a follower, mutually detachable connections between the aiming device and the follower to cause the latter to follow the aiming movements of the aiming device, said connections permitting, when in 100 the hands of the marksman, detachment of the aiming device from the follower to provide for a free upward sweep of the aiming device.

58. The combination with an aiming device of an aim recording attachment comprising a mechanical marker to follow the movement of the aiming device during aiming, an aim fixing spot at which aim may be taken, a separate bull's-eye to receive the 105 mark of the marker, a common carrier maintaining the aim fixing spot and bull's-eye in a fixed relation corresponding to the relation of the marker and the line of sight of the aiming device, and means for adjusting 110 the aim fixing spot on the carrier relatively to the bull's-eye to alter that relation.

59. The combination with an aiming device of an aim recording attachment therefor comprising a mechanical marker connected to the device to have a definite relation to its line of sight, aim fixing and aim recording means comprising an aim fixing spot at which aim may be taken, a bull's-eye to receive the mark of the marker, a 120 common holder for maintaining them in fixed position determined by the relation of the marker to the line of sight and means

provided by said holder for the adjustment of the relation between the aim fixing spot and the bull's-eye on the holder.

60. The combination with an aiming device of an aim recording attachment therefor, comprising a mechanical marker connected to the device to have a definite relation to its line of sight, aim fixing and aim recording means comprising an aim fixing target, an adjustable target holder therefor, an aim recording bull's-eye to receive the mark of the marker, and a common carrier for said bull's-eye and adjustable target holder.

61. The combination with an aiming device of an aim recording attachment comprising a marker for following the movement of the aiming device during aim, said aiming device with its marker having a free, unrestrained, positioning movement, aim fixing and aim recording means comprising an aim fixing spot at which aim may be taken, a bull's-eye to receive the mark of the marker, and a common carrier to maintain the aim fixing spot and bull's-eye in a fixed relation corresponding to the relation of the marker and the aiming device.

62. The combination with an aiming device of an aim recording attachment comprising a marker for following the movement of the aiming device during aim, said aiming device with its marker having a free, unrestrained, positioning movement, aim fixing and aim recording means comprising an aim fixing spot at which aim may be taken, a bull's-eye to receive the mark of the marker, and a common carrier to maintain the aim fixing spot and the bull's-eye in a fixed relation corresponding to the relation of the marker and the aiming device.

63. The combination with an aiming device of an aim recording attachment comprising a marker mechanically connected to the said device to follow the movement thereof during aiming, an aim fixing target with its holder at which target aim may be taken, a separate aim recording target with its holder which target is adapted to receive the mark of the marker, and a common carrier for said aim fixing target and aim recording target to maintain them in definite relation corresponding to the relation of the marker and the aiming device.

64. The combination with an aiming device of an aim recording attachment comprising a marker mechanically connected to the said device to follow the aiming movements thereof, an aim fixing spot at which aim may be taken, a separate bull's-eye to receive the mark of the marker, a common carrier to maintain the aim fixing spot and bull's-eye in definite relation determined by the relation of the marker and the aiming device, adjustment means for adjusting the aim fixing spot relatively to the bull's-eye,

and a scale for indicating the extent of adjustment.

65. The combination with an aiming device of an aim recording attachment comprising a marker mechanically connected to said device to follow the aiming movements thereof, an aim fixing spot, a bull's-eye to receive the mark of the marker, a common carrier maintaining the aim fixing spot and bull's-eye in definite relation predetermined by the relation of the marker and the line of sight of the aiming device, means providing for a vertical adjustment of the aim fixing spot on the carrier relatively to the bull's-eye to alter that relation, and a scale to indicate the extent of vertical adjustment.

66. The combination with an aiming device of an aim recording attachment comprising a marker mechanically connected to the aiming device to follow the aiming movements of the latter, an aim fixing spot at which aim may be taken, a separate bull's-eye to receive the mark of the marker, a common carrier maintaining the aim fixing spot and bull's-eye in definite relation predetermined by the relation of the marker and the line of sight of the aiming device, means for adjusting the aim fixing spot on the carrier relatively to the bull's-eye to alter that relation and a scale to indicate the extent of adjustment.

67. The combination with an aiming device of an aim recording attachment comprising a mechanical marker to follow the movement of the aiming device during aiming, an aim-fixing spot at which aim may be taken, a separate bull's-eye to receive the mark of the marker, and a common carrier maintaining the aim-fixing spot and bull's-eye in definite relation predetermined by the relation of the marker and the line of sight of the aiming device, said aim-fixing spot being vertically adjustable on the said carrier.

68. The combination with a target adapted for use with an aiming device and a mechanically connected marker of means for showing an aim-fixing spot at a distance above the bull's-eye and the target approximately equal to the distance of the line of sight above the line of action of the marker, a common carrier for the target and the aim-fixing spot, and means for adjusting the relation between the line of sight, the marker, the bull's-eye and the aim-fixing spot to offset the marker from a vertical line through the bull's-eye when the line of sight is directed on the aim-fixing spot.

69. A target practice apparatus comprising a support adapted to be attached and movable with an aiming device, and a target at which aim may be taken secured to said support.

70. A target practice apparatus comprising

ing a support adapted to be attached to an aiming device, and a target at which aim may be taken, said target being movable therewith and maintained by said support 5 at a substantially fixed distance from the aiming device.

In testimony whereof, I have signed my

name to this specification, in the presence of two subscribing witnesses.

HENRY H. CUMMINGS.
